DESIGN FOR A SLACK SUIT

Harry Silverstein, New York, N. Y.

Application March 3, 1942, Serial No. 106,065

Term of patent 3½ years

To all whom it may concern:

Be it known that I, Harry Silverstein, a citizen of the United States of America, residing in New York city, county of New York, and State of New York, have invented a new, original, and ornamental Design for a Slack Suit, of which the following is a specification, reference being had to the accompanying drawing, forming part thereof, wherein—

I claim:

The ornamental design for a slack suit, substantially as shown.

HARRY SILVERSTEIN,
